Claims priority, application Germany May 15, 1956
10 Claims. (Cl. 263—49)

This invention relates to an open-bottomed annealing hood for annealing materials such as metal sheets. Such hoods are subjected to considerable stressing due to unequal expansion and mechanical forces. One cause for such stressing which has not hitherto been mastered is the pressure exerted by the sand located in the sealing pan surrounding the base of the hood on all sides. The buckling of the walls of the annealing hood resulting therefrom cannot be avoided even by making these walls from heat-resisting, profiled plates.

The object of the invention is to rectify such demormentation of the walls of the annealing hood between annealing operations and for this purpose straightening shafts are incorporated in the devices for securing the hood in position and also for strengthening it to a considerable extent to prevent buckling. After each or several annealing operations the shafts are turned about their longitudinal axes until they are brought into a position with their bent or curved portion directed outwardly, and they then stretch the wall of the hood in outward direction and straighten it.

An arrangement capable of carrying out this straightening operation is hereinafter described by way of example with reference to the accompanying drawings, in which—

FIG. 1 is a perspective view of an annealing hood in which straightening shafts are provided along the lower edges of the two longitudinal walls for returning these longitudinal walls into a flat state;

FIG. 2 shows, also in perspective view, an annealing hood wherein shafts in the form of tubes are provided both along the longitudinal walls and also along the end walls for returning the respective walls into a flat condition;

FIG. 3 is, in the main, a vertical section through the lower edge of a longitudinal wall of the annealing hood according to FIG. 2, taken transversely to the longitudinal axis of the straightening shaft; this figure also shows the sealing pan;

FIG. 4 is a horizontal section through the two straightening shafts extending one along one longitudinal wall and the other along one end wall, the sectional plane being located through the axes of the two shafts which consist of tubes, and

FIG. 5 shows an end view of a straightening shaft extending along a longitudinal wall of the annealing along a longitudinal wall of the annealing hood.

In the form of construction of the annealing hood illustrated in FIG. 1, the end walls 1 and the longitudinal walls 2 are each composed of a one-piece profiled, heat-resisting steel plate provided with sections 10 projecting outwards from the plane of the plate. On the lower edge of each end wall 1, a bar or anchoring member 3, composed of flat iron, is fixed by means of bolts 4. This bar has at its two ends recesses 5 serving as bearings for straightening shafts 6.

The shafts 6 located in front of the lower edges of the longitudinal walls 2 rest in bearings 7 fixed on the longitudinal walls. At least two abutment rings 8 are provided on each straightening shaft for securing the shaft in axial direction. In the example illustrated three guide rings 8 are detachably and adjustably fixed on each straightening shaft. The two outer guide rings 8 bear against the

2

two flat bars 3, whereas the third guide ring bears against one of the bearings 7. The straightening shafts 6 are constructed in the form of tubes and provided with lugs or webs 9 which enable the shafts 6 to be turned after the insertion of a suitable tool. If the straightening shafts 6 are not tubes but consist of solid section rods, each shaft is mostly provided, at least at one end, with an external or internal square or hexagon for engaging a tool serving for turning the straightening shaft.

10 If, after one or several annealing operations, the longitudinal walls 2 of the annealing hood are bent inwards with their straightening shafts 6, the shafts are turned through an angle of 180° so that they pull the two longitudinal walls outwards back into a substantially straight position. At the same time the two flat iron bars 3 and the straightening shafts 6 form a union which is capable of eliminating even considerable deformation in the longitudinal walls of the hood, that is they straighten the longitudinal walls 2.

15 In the form of construction of the annealing hood illustrated in FIGS. 2 to 5 the profiled plates constituting the end walls 1 and the longitudinal walls 2 are so constructed that sections 10' projecting from the plane of the plate of each side wall are provided with bevels 11 which extend to the lower edge of the annealing hood and terminate above the lower edge thereof so that the lower edges of all the walls consist of flat surfaces.

20 The straightening shaft 6 extending parallel to these flat lower edges of the longitudinal walls 2 and also in this case the shafts 12 arranged in front of the end walls 1 of the annealing hood are accommodated in the clearance produced by the bevels 11 of the projecting sections 10', that is in front of the flat lower edges of the annealing hood and the bearings 7' for the shafts 6 as well as the bearings 13 for the shafts 12 are fixed on the receding surfaces 14 of the projecting sections so that they do not project beyond the periphery of the hood.

25 The bearings 7' and 13 are each in the form of a U-shaped strap open towards the surfaces of the walls 1 and 2 respectively (see FIG. 3) and from one arm 15 of each strap a flange 16 extends which is fixed to the surface 14 of the wall by means of bolts 17. The bolts 17 pass through the wall 14 of the annealing hood and are provided at their two ends with bearing washers 18 and 19 by means of which the straps are held on the walls of the annealing hood. The arms 15 of the bearing straps 17 are located above the straightening shafts 6 and 12. The lower arm 20 of each of the bearing straps 7' and 13 is provided with a claw 21 extending beyond and engaging behind the lower edge of the wall surface of the annealing hood and with an abutment surface 22 bearing against the outer side of the wall surface. The bearing straps 7' and 13 are slipped on to the edge of the annealing hood from below and then fixed on the walls by means of the bolts 17 and washers 18, 19.

30 At each corner of the annealing hood a connecting or angle piece 23 is provided for the longitudinal straightening shafts 6 abutting at this point with the transverse straightening shafts 12. This connecting piece which engages the lower edge of the annealing hood by means of a claw 29, has two horizontal bores at right angles to each other for receiving the straightening shafts 6 and 12.

35 The pin 26 is fixed on the tubular transverse straightening shaft 12 by means of bolts 24 and 25 arranged at right-angles to each other, which pin engages in a corresponding bore in the connecting piece 23. The tubular straightening shaft 6 rests on the end face of this pin 26. Each tubular straightening shaft 6 carries an abutment ring 27 on which the connecting piece 23 is supported with the straightening shaft 12 above the two

40

45

50

straightening tubes 6 on both sides of the annealing hood, when the end walls 1 of the annealing hood buckle inwards.

One end of the straightening shafts 6 and 12 always projects outwards at least as far as the outer end face of the connecting piece 23 and is there provided with internal recesses in which the corresponding projections of a tool engage for the purpose of turning the straightening shafts 6 and 12. The straightening shafts 6 and 12 together with their connecting pieces 23 form a frame which is connected to the lower edge of the annealing hood, each shaft being capable of straightening its co-ordinated wall of the annealing hood merely by being turned.

In FIG. 3 is illustrated the conventional sealing pan 31, containing sand 32.

I claim:

1. An annealing hood having an open bottom and a top cover for use with a sealing pan having sand surrounding the open bottom of the hood, the hood having four upwardly-downwardly extending walls formed of one piece of steel, rotatable straightening shafts carried by the hood outside thereof and adjacent the lower edges of two opposite walls thereof, anchoring members extending along and connected with the lower edge portions of the other two opposite walls, the anchoring members rotatably supporting the ends of the shaft, bearing means secured on the outer lower end portions of the first two opposite walls and disposed adjacent the lower edges of said two walls and intermediate said anchoring means, said shafts passing through said bearing means, the anchoring means and said shafts forming a frame, the shafts providing bracing means tending to diminish warping of the walls, the turning of the shafts in the bearing means tending to straighten the walls should warping have occurred.

2. The hood defined in claim 1, said anchoring means being rigid elements rigidly secured along the lower edge portions of the other two opposite walls.

3. An annealing hood having an open bottom and a top cover for use with a sealing pan having sand surrounding the open bottom of the hood, the hood having four upwardly-downwardly extending walls formed of one piece of steel, rotatable straightening shafts carried by the hood outside thereof and adjacent the lower edges of two opposite walls thereof, anchoring members extending along and connected with the lower edge portions of the other two opposite walls, the anchoring members rotatably supporting the ends of the shaft, bearing means secured on the outer lower end portions of the first two opposite walls and disposed adjacent the lower edges of said two walls and intermediate said anchoring means, said shafts passing through said bearing means, the anchoring means and said shafts forming a frame, the shafts providing bracing means tending to diminish warping of the walls, the turning of the shafts in the bearing means tending to straighten the walls should warping have occurred, and abutment means rigidly secured to opposite end portions of said shafts at points adjacent to and between the opposite anchoring means of each shaft, to secure the shafts in axial direction.

4. An annealing hood having an open bottom and a top cover for use with a sealing pan having sand surrounding the open bottom of the hood, the hood having four upwardly-downwardly extending walls formed of one piece of steel, rotatable straightening shafts carried by the hood outside thereof and adjacent the lower edges of two opposite walls thereof, anchoring members extending along and connected with the lower edge portions of the other two opposite walls, the anchoring members rotatably supporting the ends of the shaft, bearing means secured on the outer lower end portions of the first two opposite walls and disposed adjacent the lower edges of said two walls and intermediate said anchoring means, said shafts passing through said bearing means, the anchoring means and said shafts forming a frame, the

shafts providing bracing means tending to diminish warping of the walls, the turning of the shafts in the bearing means tending to straighten the walls should warping have occurred, and abutment means rigidly secured to opposite end portions of said shafts at points adjacent to and between the opposite anchoring means of each shaft, to secure the shafts in axial direction, an end of each shaft being exposed and shaped to provide gripping surface for a tool to turn the shaft.

5. An annealing hood having an open bottom and a top cover for use with a sealing pan having sand surrounding the open bottom of the hood, the hood having four upwardly-downwardly extending walls formed of one piece of ferrous metal, said walls having upwardly-downwardly extending sections projecting outwardly from

the faces of said walls, rotatable straightening shafts carried by the hood outside thereof and adjacent the lower edges of two opposite walls thereof, anchoring members extending along and connected with the lower edge portions of the other two opposite walls, the anchoring members rotatably supporting the ends of the shaft, bearing means secured on the outer lower end portions of the first two opposite walls and disposed adjacent the lower edges of said two walls and intermediate said anchoring means, said shafts passing through said bearing means, the anchoring means and said shafts forming a frame.

6. An annealing hood having an open bottom and a top cover for use with a sealing pan having sand surrounding the open bottom of the hood, the hood having four upwardly-downwardly extending walls formed of one piece of steel, said walls having upwardly-downwardly extending sections projecting outwardly from recessed face portions of said walls, rotatable straightening shafts carried by the hood outside of and adjacent the lower edges of two opposite walls thereof, anchoring members extending

along and connected with the lower edge portions of the other two opposite walls, the anchoring members rotatably supporting the ends of the shaft, bearing means carried by the lower edge portions of the recessed face portions of the first two opposite walls and disposed adjacent the lower edges of said two walls and intermediate said anchoring means, said shafts passing through said bearing means, the anchoring means and said shafts forming a frame.

7. An annealing hood having an open bottom and a top cover for use with a sealing device having sand surrounding the base of the hood, the hood having four upwardly-downwardly extending walls formed of one piece of steel, four rotatable straightening shafts carried by

the hood outside of and adjacent the lower edges of said wall, angle pieces rotatably connecting the ends of the shafts to form a frame, the angle pieces having mutually transverse bores to rotatably receive the shaft ends, and abutment rings rigidly secured to opposite end portions of a pair of said shafts at points adjacent to and between two opposite angle pieces, to secure the said pair of shafts in axial direction, bearing means rigidly carried by the four walls and disposed adjacent the lower edge portions of the four walls, said four shafts passing through said bearing means.

8. The apparatus defined in claim 7, each angle piece being provided with a holding means engaging under the lower edge of the said walls, at the respective corner.

9. An annealing hood having an open bottom and a top cover for use with a sealing pan having sand surrounding the base of the hood, the hood having four upwardly-downwardly extending walls formed of one piece of ferrous metal, said walls having four upwardly-downwardly extending sections projecting outwardly from recessed face portions of said walls, four rotatable straightening shafts carried by the hood outside of and adjacent the lower edges of said wall, four angle pieces rotatably connecting the ends of the shafts to form a frame, the angle pieces having bores to rotatably receive the shaft ends, and abutment rings rigidly secured to opposite

end portions of a pair of said shafts at points adjacent to and between two opposite angle pieces, to secure the said pair of shafts in axial direction, bearing means carried by the outer lower edge portions of the recessed portions of the four walls, said four shafts passing through said bearing means, an end of each shaft being shaped to provide gripping surface for a tool to turn said shaft.

10. An annealing hood having an open bottom and a top cover for use with a sealing pan having sand surrounding the base of the hood, the hood having four upwardly-downwardly extending walls formed of one piece of steel, four rotatable straightening shafts carried by the hood outside of and adjacent the lower edges of said wall, four angle pieces rotatably connecting the ends of the shafts to form a frame, the angle pieces having mutually transverse bores to rotatably receive the shaft ends, one of the two shafts connected by each angle piece extending in one of said bores and exposing a shaft end for appli-

cation of a rotating tool, the other of said two shafts having an end face disposed transversely to and adjacent an end portion of said one of the two shafts, and abutment rings rigidly secured to opposite end portions of a pair of said shafts at points adjacent to and between two opposite angle pieces, to secure the said pair of shafts in axial direction, bearing means rigidly secured to the outer lower edge portions of the four walls, said four shafts passing through said bearing means and forming with said angles a frame disposed about and outward of said walls.
